UNITED STATES PATENT OFFICE.

JAMES L. BERNARD, OF BEAVER, PENNSYLVANIA.

ELECTRIC FURNACE.

Application filed December 15, 1926. Serial No. 154,961.

- This invention relates to electric furnaces, and more particularly to electric furnaces in which the tops or roofs may be removed for the purpose of charging, and has for its 5 object the provision of an improved furnace construction of this class having improved means for raising and lowering the furnace roof and having a novel mounting for the furnace body.
- 10 Another object is to provide a furnace having the novel design, construction and combination of parts hereinafter described and illustrated in the accompanying drawings.

15 In the drawings:

Figure 1 is a side elevation of a furnace constructed in accordance with this invention.

20 Figure 2 is a front elevation thereof.

Figure 3 is a plan or top view thereof.

Figure 4 is a sectional plan on the line IV—IV of Figure 2.

Referring more particularly to the drawings, the numeral 2 designates the furnace body, and 3 designates the furnace roof. The furnace body 2 has the usual pouring spout 4, and slagging spout 5, together with the usual hearth and fire-brick lining (not shown), and is mounted on a movable truck 25 A, consisting of side frames 6 connected together by cross members 7. The truck A, is provided with flanged wheels 8, and is adapted to be propelled by a motor 9 along a track 10 and track sections 12 on a tilting base or cradle B.

The cradle B consists of side beams 13 having the track sections 12 thereon and connected together by cross members 14. Side frames 15 and 16 extend upwardly from the 40 side beams 13 of the cradle and are joined at their tops by cross beams 17.

The side beams 13 of the cradle B are provided with integral rack portions 18 which are meshed with rack portions 19 on foundation beams 20 which are mounted on concrete supports 21.

50 The cradle B is connected by a rod 22 to a crank 23, which crank is preferably power driven to tilt the cradle B and furnace mounted thereon for slagging and pouring.

Bumper blocks 24 are bolted or otherwise secured to the side beams 13 of the cradle to stop and center the furnace body 2 with respect to the furnace top or roof 3.

55 The furnace roof 3 is of the usual construction of fire-brick bound and reinforced by

steel with openings 25 through which electrodes 26 pass into the furnace. Suitable standard mechanism 26^a is mounted on the side frame 15 for raising and lowering the 60 electrodes 26.

The roof 3 is connected by adjustable and flexible links 27 to one arm of bell cranks 28 which are pivotally secured to brackets 29 on cross beams 17. The other arms of bell 65 cranks 28 are connected in pairs by connecting rods 30, and each pair of bell cranks are connected by a link 31 to one arm of an operating bell crank 32. The other arm of each of the bell cranks 32 are connected by 70 rods 33 to cranks 34, which cranks are keyed to a shaft 35 driven by a motor 36 through a speed reducer 37, pinion 38 and gear 39. The cranks 34, shaft 35, motor 36 and gearing above described, are all supported on the 75 side frame 16 of the cradle.

A pair of guide castings 40 are secured to the roof 3 at diametrically opposite points, and adapted to engage with guide castings 41 bolted or otherwise secured to the side 80 frames 15 and 16 of the cradle. The guide castings 40 and 41 serve to hold the roof 3 in position when it is raised or lowered and also while the furnace is being poured.

Locking pins 42 are suspended by chains 85 43 or other suitable flexible members from the roof guide castings 40. The pins 42 pass through apertured lugs 44 secured to the side frames 15 and 16, and engage in lugs 45 secured to the furnace body 2. The pins 42 90 and lugs 44 and 45 serve to lock the furnace body 2 to the cradle so as to prevent movement of the furnace relative to the cradle B when the cradle is tilted.

In operation, starting with the furnace 95 body 2 and truck A moved out of the cradle and onto the track 10 for charging, as shown at C, Figure 1. The charge is placed on the hearth, and the truck A is propelled onto the cradle so as to align with the roof 3. The 100 roof 3 is then lowered into position on the furnace body 2 by operation of the bell cranks 28 and 32. As the roof 3 is lowered onto the furnace body 2, the locking pins 42 will enter the lugs 45, thus locking the furnace body 2 to the cradle B. The electrodes will then be lowered into position and the charge melted. After the charge is melted and ready to pour, the electrodes are raised and the furnace tilted by rocking the cradle 110 B to slag and pour the metal. After the metal is poured the cradle will again be

brought to a horizontal position, and the roof 3 is raised, thus removing the pins 42 from the lugs 45, and freeing the furnace body so that it may be again moved onto the track 10 for charging.

While I have shown one specific embodiment of my invention, it will be understood that I do not wish to be limited thereto, since various modifications may be made without departing from the scope of my invention as defined in the appended claims.

I claim:

1. In an electric furnace, comprising a tilting base, tracks on said base, a frame extending upwardly from said base, a wheel supported furnace body adapted to be run on said tracks into and out of position in said frame, a vertically adjustable roof carried by said frame, means for adjusting said roof, and means for locking said furnace body in position in said frame.

2. In an electric furnace, comprising a tilting base, tracks on said base, a frame extending upwardly from said base, a wheel supported furnace body adapted to be run on said tracks into and out of position in said frame, a vertically adjustable roof carried by said frame, power operated mechanical means for adjusting said roof, and means suspended from said roof and cooperating with other means on said frame and said furnace body for locking said furnace body in position in said frame.

3. In an electric furnace, comprising a tilting base, tracks on said base, a frame extending upwardly from said base, a wheel supported furnace body adapted to be run on said tracks into and out of position in said frame, a vertically adjustable roof carried by said frame, power operated mechanical means for adjusting said roof, locking pins suspended from said roof and slidably mounted in blocks secured to said frame, and apertured blocks secured to said furnace body, said pins being adapted to enter the

apertures in said blocks on said furnace body and lock said furnace body in position in said frame.

4. In an electric furnace, comprising a tilting base, tracks on said base, a frame extending upwardly from said base, a wheel supported furnace body adapted to be run on said tracks into and out of position in said frame, a vertically adjustable roof carried by said frame, means for adjusting said roof, said means including a plurality of bell cranks mounted on said frame and having one arm connected to said roof, and means connected to the other arm of each of said bell cranks for rocking said bell cranks to adjust said roof.

5. In an electric furnace, comprising a tilting base, tracks on said base, a frame extending upwardly from said base, a wheel supported furnace body adapted to be run on said tracks into and out of position in said frame, a vertically adjustable roof, a plurality of bell cranks pivotally supported on said frame, adjustable flexible supporting members connected to said bell cranks and to spaced points of said roof, and power means for rocking said bell cranks to adjust said roof.

6. In an electric furnace, comprising a tilting base, tracks on said base, a frame extending upwardly from said base, a wheel supported furnace body adapted to be run on said tracks into and out of position in said frame, a vertically adjustable roof, a plurality of bell cranks pivotally supported on said frame, adjustable flexible supporting members connected to one arm of each of said bell cranks and to said roof, said bell cranks being connected in pairs by connecting rods connected to their other arms, and power means for rocking said bell cranks to raise and lower said roof.

In testimony whereof, I have hereunto signed my name.

JAMES L. BERNARD.
